SNOW SCREEN

Filed April 18, 1927

UNITED STATES PATENT OFFICE

LOUIS C. REIS, OF DULUTH, MINNESOTA

SNOW SCREEN

Application filed April 18, 1927. Serial No. 184,626.

This invention relates to a new and improved fence construction, and more particularly to such a construction adapted for use as a snow fence.

In certain sections of the country it is necessary to provide snow fences along highways and railroads to prevent drifting of snow on to the highways and railroads. The fences cause drifting adjacent to them and must be spaced away from the railroad or highway so that the drift will not be formed thereon. For this reason in many localities it is necessary to place the snow fences in cultivated fields. Since the fence would prevent the use of portions of the fields it is customary to remove the fences during the summer. Also during periods of extended drifting it may be desirable to lift the fence and move it back further from the road or highway being protected. These fences as now commonly constructed, are formed of wood which is subject to heavy loss from breakage and also from fire. The wood fence is usually made in panels which are removed and stacked during the summer, and this moving and handling causes considerable loss.

It is an object of the present invention to provide a fence adapted for snow fence uses, which is formed entirely of metal and which may be readily removed and replaced.

It is a further object to provide a fence of this character which may be rolled for storage and which will then occupy but small space.

Other and further objects will appear as the description proceeds.

I have illustrated in the accompanying drawings certain preferred embodiments of my invention.

In the drawings—

Figure 1 is a face view of a section of one form of fence;

Figure 2 is a section taken on line 2—2 of Figure 1;

Figure 3 is a face view of a modified form of fence;

Figure 4 is a section on an enlarged scale taken on line 4—4 of Figure 2;

Figure 5 is a fragmentary view on an enlarged scale of one of the intermediate metal members of one form of the fence;

Figure 6 is a transverse section taken on line 6—6 of Figure 5;

Figure 7 is a view similar to Figure 5 but showing a modified form of construction; and

Figure 8 is a section taken on line 8—8 of Figure 7.

The form of construction shown in Figures 1 and 2 comprises a plurality of post sections 11 connected by a plurality of transverse wires 12. The intermediate metal members or pickets 13 are secured to the wires 12 by clips 14. Clips 14 are also used for securing the wires to the posts 11.

The posts 11 are shown in detail in cross section in Figure 4. They have the face portion 15 provided with the serrated upturned edges 16. The post is T-shaped in cross section having the rearwardly extending leg 17, the outer edge of which is formed with the bulb 18. This post has quite considerable resistance of bending in any direction.

One form of intermediate member or picket is shown in Figures 5 and 6. It consists of a flat face portion having upturned serrated edges 19. It is shown as a light rolled section generally similar to the face portion of the posts 11 but somewhat wider and lighter.

Another form of intermediate picket is shown in Figures 7 and 8. This picket 20 is corrugated in form as best shown in Figure 8. It is provided with an intermediate depressed portion 21, with outwardly rounded portions 22 and with inturned serrated edge portions 23. This form of picket may be rolled and cut from sheet metal and thus is lighter and cheaper to produce than the rolled section of Figures 5 and 6. Due to its corrugated form, however, it possesses considerable rigidity. This form of picket is shown held between two wires twisted together rather than held to single wires by clips. Obviously, however, either form of picket may be supported in either way.

In Figure 2 the fence is shown as supported by the backwardly extending legs 24 which are connected by links 25 to the upper ends of the posts 11. The lower ends of the legs and posts are shown as extending a short distance into the ground. It will be understood that for shipping the legs 24 would be

folded against the posts 11 and that the whole fence structure may then be readily rolled for shipment or storage.

The form of construction shown in Figure 3 is provided with posts 11' which extend for some distance beyond the lower edge of the intermediate pickets. These lower portions 26 of the posts are provided with spades 27 to aid in holding the post in the ground. It will be 10 understood that this form of fence is not provided with the supporting legs of Figure 2 but is held in the ground and supported by the post extensions and spades or anchors. It is possible, however, to remove this fence 15 for storage or shipment by an upward pull upon the fence post which will draw the post and spade up out of the ground.

While I have shown certain preferred forms of posts and pickets, it will be understood 20 that these forms may be further modified and I contemplate such changes and modifications as come within the spirit and scope of the appended claims.

I claim:

- 25 1. Fence construction, comprising metal posts, wires connecting said posts and metal pickets, the metal pickets being connected to the wires intermediate the posts, legs hingedly connected to the posts, the posts and pickets 30 being so connected to the wire as to permit the entire structure to be rolled for shipment.
2. Fence construction, comprising a plurality of parallel wires, metal members extending transversely of the wires and secured 35 to the wires in spaced relation, certain of the metal members being longer than the others and adapted to serve as posts when the fence is erected and legs hingedly connected to the longer metal members.
- 40 3. Snow screen construction comprising a plurality of parallel wires, members extending transversely of the wires and secured to the wires in spaced relation, certain of said members having ends extending beyond the 45 adjacent members, and legs pivotally secured to said extending members and adapted to be folded against said members when the structure is rolled for shipment.
4. Snow screen construction comprising a 50 plurality of parallel wires, metal members extending transversely of the wires and secured to the wires in spaced relation, certain of the members having legs pivotally secured thereto, said legs being adapted to be folded against the members when the structure is rolled for shipment.
5. Snow screen construction comprising a 55 plurality of parallel wires, metal members extending transversely of the wires and secured to the wires in spaced relation, certain of the members having rearwardly extending flanges whereby their resistance to bending is increased, and legs pivotally secured to said flanges, said legs being adapted to be 60

folded against the members when the structure is rolled for shipment.

Signed at Duluth, Minnesota, this 11th day of April, 1927.

LOUIS C. REIS.
